UNITED STATES PATENT OFFICE

ARTHUR R. STOWELL, OF GREENWOOD, MAINE

TARGET

Application filed November 28, 1930. Serial No. 498,846.

This invention relates to targets for practicing marksmanship, and it has for its object the provision of a disk or similar body having an impaling point by which it may be stuck to a wall or fence, and which when hit will fracture, the impaling point being of such inconsiderable length that it will be jarred out of the wall when the target is struck, falling with the piece of target in which it may be fixed, so that the wall is completely cleared of the débris of the shattered target.

Another object of the invention is to provide a headless pin for the target so that there is no metallic surface from which a glance shot may ricochet nor is there more than an infinitesimal chance of the pin being driven into the wall by the impact of the shot.

20 A further object of the invention is to provide a target in which the pin extends only part way through the thickness of the target, so as to protect the pin from being directly hit, the further to ensure that the pin shall not be driven into the wall but that the target shall first be broken and the pin fall with the pieces.

Other objects of the invention will appear as the following description of practical embodiments thereof proceeds.

30 In the drawings in which the same characters of reference have been used throughout the several figures to designate identical parts,

35 Figure 1 is a perspective view illustrating the use of the target;

Figure 2 is a back view of one form of target;

40 Figure 3 is a cross section taken along the line 3—3 of Figure 2;

Figure 4 is a back view of a modified form of target; and

45 Figure 5 is an edge view, partly in elevation and partly in section to show the embodiment of the pin.

Referring now in detail to the several figures, and first advertiring to that form of the invention shown in Figures 2 and 3, the numeral 1 represents the disk which may be 50 made of any suitable frangible material. It

is here shown as formed of wood cut across the grain. It is evident that when this is struck by a bullet it will shatter into pieces.

The rear of the target is provided with a pin 2 embedded partly in the material of the 55 target and projecting for a short distance. The projecting portion being short is preferably cylindrical so that it will not wedging-ly fail to remain in the body into which it is thrust. The target is designed to be stuck 60 to a suitable vertical surface such as a wall or a wooden fence. The projecting portion 3 of the pin 2 is of such inconsiderable length as to ensure that the piece to which the pin 65 is fixed will drop off of the wall carrying with it the pin when the target is shattered by a bullet.

The pin 2 is headless so that it will not present a flat hard surface against which a bullet might ricochet. The pin 2 extends 70 only partially through the thickness of the target, so that it is not exposed on the face thereof, the frangible material extending over the pin and protecting it from being directly hit by a bullet. This ensures that even 75 when the target is hit directly over the pin, the target will break first, the piece to which the target is fixed falling with the pin and preventing the latter from being driven into the wall.

80 In that form of the invention shown in Figure 4, the details of construction are the same as that of the modification previously described, the only difference being that the pin instead of being centrally located, is eccentrically positioned with respect to the target so that the latter may be said to be suspended from the wall. This form of the invention has the advantage that a greater proportion of the mass of the target lies below 85 the pin than above it, so that the attachment of the pin to the wall is more stable and on that account a somewhat shorter pin may be employed.

90 It is apparent from the above description that the invention although simple is invested with a number of advantages growing out of the use of the device as a target and which are new and inobvious with respect to some- 95 100

what similar devices used for other purposes.

What I claim is:

Target comprising a thin wooden plate cut cross grain with the edges of the grain presented in its front face, and a headless pin imbedded part way only in the thickness of said plate having a portion projecting from the rear face of said plate of a length just sufficient to give the target a slight hold when 10 the pin is stuck into a vertical surface.

In testimony whereof I affix my signature.

ARTHUR R. STOWELL.
